UNITED STATES PATENT OFFICE

128,191

DESIGN FOR A DOMESTIC WATER HEATER

Ernst R. Koppel, Wauwatosa, Wis.

Application December 21, 1940, Serial No. 97,525

Term of patent 14 years

To all whom it may concern:

Be it known that I, Ernst R. Koppel, a citizen of the United States, residing in the city of Wauwatosa, in the county of Milwaukee and State of Wisconsin, have invented a new, original, and ornamental Design for Domestic Water Heaters, of which the following is a specification, reference being had to the accompanying drawing, forming part thereof.

The figure is a front elevation of a domestic water heater showing my new design, the sides and rear portions of the heater being substantially plain except for the circumferential lines which follow around from the front at the top and bottom.

I claim:

The ornamental design for a domestic water heater, substantially as shown and described.

ERNST R. KOPPEL.
